UNITED STATES PATENT OFFICE.

HENRY F. HAGER, OF CHICAGO, ILLINOIS, ASSIGNOR OF ONE-HALF TO JOSEPH H. KOSNICK, OF CHICAGO, ILLINOIS.

BED-SPRING FABRIC

1,110,774.

Specification of Letters Patent. Patented Sept 15, 1914.

Application filed January 22, 1914. Serial No. 814,288.

To all whom it may concern:

Be it known that I, HENRY F. HAGER, a citizen of the United States, residing at Chicago, in the county of Cook and State 5 of Illinois, have invented certain new and useful Improvements in Bed-Spring Fabrics, of which the following is a specification.

My invention relates in general to bed-10 spring fabrics and more particularly to the type generally known as "diamond or half-diamond link" fabrics.

A principal object of the invention is the provision of a bed-spring fabric which will 15 be strong and durable and which will possess a maximum transverse and longitudinal elasticity.

While numerous diamond or half-diamond fabrics have been constructed prior to 20 my invention, these have all, so far as I am aware, been constructed of a plurality of 25 units of wire having one or more sharp or relatively sharp angular bends between the portions of the units which move relatively with regard to each other in the elastic play 30 of the fabric in use. This construction has materially shortened the life of the fabric by reason of breakage at these bends.

It is also a principal object of this invention 35 to provide a diamond link fabric composed of a plurality of units so constructed and arranged in the fabric that bends of this sort will be entirely eliminated and the provision of a stronger and more durable 40 fabric thereby attained.

Fabrics of this sort are ordinarily and 45 preferably secured in the frame by a plurality of coil springs of helical form, each of which engages the frame at one end and the fabric at the other. In the fabrics constructed prior to my invention the number of these springs required for a given width of fabric and the number of units of a given size required to produce the width have been 50 fixed and definite and could not be increased or diminished except within extremely narrow limits without so great a sacrifice of efficiency as to render the spring valueless.

A further object of my present invention 55 is the provision of a bed-spring fabric which may be made narrower or wider within wide limits as the commercial conditions in the trade require without the removal or addition of any of the wire units and without any appreciable alteration in the strength

or durability of the fabric. This increase or diminution of the width of the fabric will materially affect the number of springs required to fasten it in the frame. A reduction in the number of helical springs or a 60 widening of the fabric without the addition of units thereto provides only a slightly weaker and poorer spring and the loss in this respect is believed to be materially less than has heretofore been possible under like 65 conditions with the fabrics in use prior to my invention partly by reason of the fact that the units embodying my invention may operate with equal efficiency individually in the wider or the narrower fabric. 70

A further object of the invention is the provision of a bed-spring fabric of the type already described, which will be composed of strong and durable units and which will be easy to assemble, attractive in appearance 75 and cheap to manufacture.

Other objects and advantages of the invention will be apparent as it is better understood from the following description when considered in connection with the accompanying drawing illustrating a preferred embodiment thereof.

On the drawings, Figure 1 is a partial top plan view of a bed spring in which is secured a fabric embodying my present invention; Fig. 2 is a vertical sectional view taken substantially on the line 2—2 of Fig. 1; Fig. 3 is an enlarged perspective view of one of the wire units forming the fabric disclosed in the other figures, and Fig. 4 is a partial top plan view showing a somewhat modified embodiment of my invention.

For the purposes of illustration the fabric, generally designated as 11, is disclosed in Figs. 1 and 2 as secured in a frame 12 of any well-known or preferred construction by means of a plurality of helical springs 13 of the form ordinarily employed for this purpose. These springs in accordance with the usual custom have one end 130 threaded through suitably formed and positioned eyes 15 in the frame 12 and have the other end 16 connected directly with the fabric. The fabric in the present instance consists primarily of a plurality of inter- 135 engaged wire units or links 17 of substantially uniform shape, each of which consists of a single piece of wire bent in the manner shown in Fig. 3. Viewing this figure it will be noted that a pair of diverging 140

legs 18 of substantially the same length merge at their adjacent ends 19 into two outwardly extending coiled loops 20 which in turn merge into a straight central portion 21 disposed at right angles to the axis of said link or united, which, as will be later understood, constitutes a tension member and which lies beneath the adjacent ends 19 of the legs 18. In the fabric the units 17 are arranged in rows, which in the present instance are disposed transversely of the fabric from one side to the other with the legs 18 all extending toward one end of the fabric. Each leg 18 is bent back upon itself 15 at its outer end to provide a hook 18' which is engaged in a loop 20, the two legs of each unit being engaged with two adjacent loops 20 of adjacent units in the next adjacent row, except that the legs 18 of the 20 end row at one end of the fabric are engaged with fastening members 22 bent to provide a central loop 23 in which an end 16 of an appropriate helical spring 13 is engaged and to provide also outer loops 23' in which the 25 adjacent legs of two units are engaged. At the other end of the fabric somewhat longer wire fastening means 24 are provided and these are bent to permit engagement at their center by an end 16 of a spring 30 13 and are each hooked at their ends through adjacent loops 20 of two units 17 of the end row at this end of the fabric.

In the embodiment of the invention shown in Figs. 1 and 2 the fabric is given 35 a band edge which consists of a strip of metal 25 perforated at intervals at 26 and in each perforation 26 is arranged a leg 18 of one unit and a link 27, one end of the link being connected with an adjacent unit 40 occupied loop 20 of an appropriate unit. The ends of this band are secured in the frame by helical springs 28 which are positioned like and resemble in all respects the helical springs 13.

45 In Fig. 4 the fabric is shown as provided with a link edge instead of a band edge as shown in Figs. 1 and 2. This edge is provided by making the outer legs 31 of the links, which are located at the edge of the 50 fabric, much longer than the inner legs 32 and much longer also than the legs 33 of the units 34 forming the body of the fabric. It will be noted by viewing Fig. 4 that only every other row disposes a unit 55 at the edge of the fabric and the legs 31 are made of sufficient length to engage the loop 35 of the next link 29 at the edge of the fabric. The legs 31 are disposed substantially in a straight line and give the fabric 60 a smooth even edge. A similar elongation of a leg 37 of the fastening member 36 is provided to engage the loop 35 of the adjacent edge unit 29. The body portion of the fabric shown in this figure and the 65 means of fastening it in place are identical

with that of the embodiment shown in Figs. 1 and 2 and detailed description thereof is not thought to be necessary.

It will be noted in viewing Figs. 1 and 4 that the units when assembled provide a plurality of diamond shaped openings, each bounded on two sides by a pair of legs of a single unit and the adjacent legs of the two adjacent units to which the diverging legs of the first-mentioned unit are connected. 75 As the amount of divergence given the legs 18 and 33 of the units governs the width of a fabric having a given number of units in each row, it will be readily apparent that increasing or diminishing the degree of divergence will widen or narrow the fabric as desired and these variations in width will not increase or diminish the number of springs required to fasten such fabric in place, it only being necessary that the eyes 80 15 in the frame be appropriately positioned. The number of units in each row may be varied without altering the width of the fabric and such variations will necessarily be accompanied by an altered number of 85 springs. The arrangement at the adjacent ends of the diverging legs of each unit permits the changes in the fabric hereinbefore suggested to be accomplished without affecting appreciably the strength or durability 90 of the finished spring by reason of the fact that the legs may diverge any desired amount without imposing upon the wire or other material forming the units any undue strain at the juncture of the legs. It will be 100 apparent also that the portions 21 beneath the legs and connecting the loops 20 act as tension members when the fabric is in use and thereby materially strengthen the fabric transversely and prevent in large degree 105 distortion of the links when a weight is suddenly applied to the spring. It will be manifest also that each unit is provided with no sharp angles which connect relatively moving portions thereof, so that as the fabric is alternately stretched and permitted to return to its normal condition in use no connected parts move in such a manner as to 110 eventually weaken the material and cause a fracture at their connection.

115 I claim:

1. A bed-spring fabric of the diamond or half diamond link type, comprising a plurality of interengaged units each comprising a pair of diverging legs connected at their 120 adjacent ends to a pair of outwardly extending and coiled loops connected by a bar, the other ends of said legs being engaged in the loops of two similar units.

125 2. A bed-spring fabric of the diamond or half diamond link type, comprising a plurality of interengaged units each comprising a pair of diverging legs, the adjacent ends of said legs being connected to a pair 130 of outwardly extending coiled loops connect-

ed together by a tension bar, and the other ends of said legs being engaged in adjacent loops of two similar units.

3. A bed-spring fabric of the diamond or half diamond link type, comprising a plurality of interengaged units, one of said units comprising a pair of diverging legs connected at their adjacent ends to a pair of coiled loops, and a straight tension bar connecting said loops and disposed at right angles to the axis of said unit, the other ends of said legs being engaged with adjacent loops of two similar units.

4. A bed-spring fabric of the diamond or half diamond link type, comprising a plurality of interengaged units, one of said units being provided with diverging legs coiled at their adjacent ends into loops, and a tension bar connecting said loops and disposed beneath said legs, the other ends of said legs being engaged with adjacent loops of two similar units.

5. A bed-spring fabric of the diamond or

half diamond link type, comprising a plurality of interengaged units arranged in two rows, one of said units comprising a pair of diverging legs connected to a pair of outwardly extending connected coiled loops at their adjacent ends, said loops being connected by a rigid bar, the other ends of said legs being connected in adjacent loops of two similar units of an adjacent row.

6. A bed-spring fabric of the diamond or half diamond link type, comprising a plurality of interengaged wire units, each formed of a single piece of wire having a straight central portion, said piece of wire being coiled adjacent said central portion to provide a loop at each end thereof and to provide diverging legs beyond said loops, said legs being engaged in adjacent loops of two similar units.
